ATTORNEY.

UNITED STATES PATENT OFFICE.

JOHN G. ROHRIG, OF BENNETT, IOWA.

TONSIL-ENUCLEATER.

1,323,104.

Specification of Letters Patent. Patented Nov. 25, 1919.

Application filed August 5, 1919. Serial No. 315,473.

To all whom it may concern:

Be it known that I, Dr. JOHN G. ROHRIG, a citizen of the United States, residing at Bennett, in the county of Cedar and State 5 of Iowa, have invented new and useful Improvements in Tonsil-Enucleators, of which the following is a specification.

This invention relates to improvements in surgical instruments, and the principal object of the invention is to provide means for 10 facilitating the removal of tonsils.

Another object of the invention is to provide means whereby the cutting member may be placed in engagement with the tonsils without releasing the pliers from the 15 tonsils.

The invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying 25 drawings wherein like characters denote like or corresponding parts throughout the several views, and in which:—

Figure 1 is an elevation of the device with 30 parts in open position;

Fig. 2 is a like view with the parts in partly closed position in full lines and in closed position in dotted lines;

Fig. 3 is a view of the cutting member and 35 its handle;

Fig. 4 is an edge view of part of the supporting member;

Fig. 5 is a section on line 5—5 of Fig. 1;

Fig. 6 is a section on line 6—6 of Fig. 1;

40 Figs. 7 and 8 are detail views of the locking plate and hinge plate.

In these views 1 indicates the supporting member which is of substantially right angular form with the part 2 of channel shape 45 for a portion of its length and with its end portion forked as at 3. The extremities of each of the forks are each provided with a pair of outwardly curved prongs 4. The other part 5 of the supporting member is 50 provided with the hand engaging loop 6 and midway its ends ears 7. The handle part 8 of the cutting member is pivoted between said ears by means of the pin 9 which is carried by the plate 10. This plate is 55 provided with the slot 11 which engages with the pin 12 on said handle 8 and the

other end of the plate carries the pin 13 which engages with the elongated opening 14 in the end of the cutting member 15. The shank of this cutting member engages the 60 channel in the part 2 of the supporting member so that when the handle 8 is manipulated said cutting member will have sliding movement within said channel. The cutting part of the member consists of a 65 ring 16 which has an opening 17 in its lower wall, said opening being so located that when the cutting member is in open position said opening will lie immediately in front of the end of the lower prongs of the 70 supporting member as shown in Fig. 1. The inner half of the ring member is of the same diameter as the prongs as shown in Figs. 1 and 2. When the cutting member moves slightly, the opening 17 will pass between 75 the prongs so that the opening formed by the prongs and ring member will be closed and the parts are held in this position by means of the spring plate 18 held on the upper edge of the part 2 of the supporting 80 member by the loop 19 and having its lug 20 engaging a notch 21 formed in the upper edge of the shank of the cutting member 15.

In using the device it will be seen that the cutting ring may be slipped over the pliers 85 without releasing the tonsils and then by pressing the handles together the cutting member is moved along the supporting member until the ring reaches the position shown in dotted lines in Fig. 2. Thus the 90 tonsils will be severed.

It is thought from the foregoing description that the advantages and novel features of my invention will be readily apparent.

I desire it to be understood that I may 95 make changes in the construction and in the combination and arrangement of the several parts, provided that such changes fall within the scope of the appended claims.

What I claim is:

1. A device of the class described comprising a cutting member having a ring-shaped blade provided with an opening leading to the interior of the ring, and a forked member slidably supporting the cutting member and having its fork co-operating with the cutting member. 100

2. A device of the class described comprising a cutting member having a ring-shaped blade provided with an opening in 110 its bottom wall, a channel-shaped supporting member slidably receiving the cutting

member and having its end forked and the forks provided with prongs and an actuating handle for said cutting member.

3. A device of the class described comprising an angle-shaped supporting member having a hand opening on one part and its other part being of channel shape with its ends forked and the forks provided with prongs, a cutting member having a shank 10 and a ring-shaped blade, said ring having an opening in its wall, the shank sliding in the channel, a handle pivoted intermediate its ends to the handle part of the angle member and a pin pivotally connecting said handle 15 member to the end of the shank of the cutting member.

4. A device of the class described comprising an angle-shaped supporting member having a handle formed on one part and its other part of channel shape, ears formed on 20 the part carrying the handle, a cutting member slidably engaging said channel part, a handle, a pin pivoting the same between the ears, a plate carrying said pin, a second pin carried by the plate and connecting the 25 handle with the cutting member, said plate having a slot therein and a pin on the handle engaging said slot for holding the plate to the handle.

In testimony whereof I affix my signature. 30

DR. JOHN G. ROHRIG.
